UNITED STATES PATENT OFFICE.

HERBERT J. FRINK, OF HOLYOKE, MASSACHUSETTS, ASSIGNOR TO HOLYOKE MACHINE COMPANY, OF HOLYOKE, MASSACHUSETTS, A CORPORATION OF MASSACHUSETTS.

WOOD-PULP GRINDER.

1,311,117. Specification of Letters Patent. Patented July 22, 1919.

Application filed April 26, 1919. Serial No. 292,832.

To all whom it may concern:

Be it known that I, HERBERT J. FRINK, a citizen of the United States of America, residing at Holyoke, in the county of Hampden and State of Massachusetts, have invented certain new and useful Improvements in Wood-Pulp Grinders, of which the following is a specification.

This invention relates to improvements in wood pulp grinders and more particularly to improvements in the means employed for forcing the wood against the grindstone.

Originally, grinders of this character were provided with wood pockets, which were designed to take short lengths of wood. With such short lengths of wood, there was seldom any material variation in diameter throughout the length of the wood. More recently, however, a demand has arisen for grinders having wood pockets which are capable of receiving wood of relatively long length and the obstacle to using such long lengths of wood is the appreciable and very material variation, which exists between one end of the wood and the other. Obviously, with the ordinary grinder, the wood, when of variable diameter throughout its length, will not be forced against the grindstone with uniform pressure.

That the difficulty mentioned constitutes a real problem in the development of grinders for the production of wood pulp is evidenced by the prior art, wherein it has been proposed to provide with each single wood box two or more pressure devices, each acting independently of the other to force the wood against the grindstone with uniform pressure despite material variations of diameter from end to end in the wood.

This invention is concerned with another and improved solution for the stated problem and, more particularly with the provision of means for overcoming the prior difficulties in a much less expensive manner.

According to my invention, I provide, in connection with each wood box and its pressure device, a follower which is connected to the pressure device for limited swinging movement and which may, therefore, conform to the taper of the wood engaged by it in the wood box.

Other features and advantages will appear in the following description and in the illustrative embodiment of the invention in the accompanying drawings, in which—

Figure 1 is a front elevational view, with parts in section, of a wood pulp grinder, embodying my invention;

Fig. 2 is a partial cross sectional view thereof; and

Figs. 3 and 4 are enlarged sectional views showing the pressure device, follower and wood box in the positions shown in Figs. 1 and 2 respectively.

Referring to these drawings, there is shown, in Figs. 1 and 2 and in conventional form, such elements of a wood pulp grinder as are necessary to an understanding of the invention. A represents the frame of the machine and g the grindstone rotatably mounted therein. Adjacent the periphery of stone g are one or more wood pockets w (as illustrated, three in number) and associated with each pocket w is a pressure device, which consists of a cylinder e, a piston p, and piston rod r. Associated with the piston rod r is a follower f, which directly engages the wood x and forces it against the periphery of the grindstone g.

The parts thus far described are common in grinders for the production of wood pulp and are so well understood in the art that further and detailed description of their structure and mode of operation is unnecessary. It has also been thought unnecessary to illustrate the usual and more or less elaborate mechanism associated with the admission or control of the fluid used to force the piston p radially inwardly toward the grindstone g. Obviously, any suitable means may be provided for this purpose and many examples of suitable means will be found in the prior art.

The grinder illustrated is characterized in that the stone g is of greater width and the wood pocket w of greater length than usual. The pocket w is designed to receive relatively long lengths of wood and wood of such length that there is an appreciable and material variation in diameter from end to end thereof. To provide for the forcing of such wood against the grindstone g with a substantially uniform pressure, I provide an improved means of connecting the follower f to the pressure device, or to the piston rod r thereof.

Such improved means consists essentially in pivoting the follower to the rod so that it may swing relatively thereto to conform to the taper of the long lengths of wood, as

clearly illustrated in Fig. 2. Thus, the follower *f* has two spaced webs or upstanding flanges 10 thereon, between which is received a member 11 suitably fixed on the lower end 5 of rod *r*, and the member and flanges are connected by a pivot pin 12. Preferably, the swinging movement of the follower *f*, as thus provided for, is limited in each direction by abutments 13, provided on the member 10 11 and arranged one on each side of the pivot pin 12. Such abutments function by engagement with the upper face of the follower to arrest the latter after it has traversed a predetermined arc of swinging 15 movement. The degree of swinging movement will, of course, vary according to the particular character of the wood used in box *w*, particularly its length, but, for any given character of work, the desired limits can 20 be predetermined and the abutments 13 so disposed with relation to the follower as to insure the proper limiting of its swinging movement.

In operation, fluid is admitted to cylinders *c* above the pistons *p*, whereupon they move radially inward toward the rotating stone *g*. After the follower *f* has first engaged the wood in box *w*, it is tilted on, continued movement until it engages the entire 25 length of the wood *w*, whereby the pressure will be uniformly distributed upon the wood throughout the length of box *w*.

The invention has been disclosed herein, in an embodiment at present preferred, for 30 illustrative purposes, but the scope of the invention is defined by the appended

claims, rather than by the foregoing description.

What I claim is—

1. In a wood pulp grinder, a rotary grindstone, a pocket to hold the wood to be ground, a follower to force the wood against the stone, an actuating means for the follower, a hinge connection between the follower and actuating means restricting the former to swinging movement in a single plane and to and from the stone, and stops to limit the swinging movement of the follower in each direction.

2. In a wood pulp grinder, a rotary grindstone, a pocket to hold the wood to be ground, a pressure cylinder, a piston and piston rod therefor, a follower to force the wood against the stone, means connecting the follower to the rod for swinging movement to and from the stone, and means independent of said connecting means to limit the swinging movement of the follower.

3. In a wood pulp grinder, a rotary grindstone, a pocket to hold the wood to be ground, a pressure cylinder, a piston and piston rod therefor arranged to force the wood against the stone, a follower through which the pressure is transmitted from the rod to the wood, said follower being pivoted to the rod for swinging movement to and from the grindstone, and abutments carried by the rod and disposed on opposite sides of the pivot to limit the swinging movement of the follower.

HERBERT J. FRINK.
